UNITED STATES PATENT OFFICE.

CHARLES BEAUMONT, OF ROUBAIX, FRANCE.

HAIR-PIN-MAKING MACHINE.

SPECIFICATION forming part of Letters Patent No. 594,844, dated December 7, 1897.

Application filed September 10, 1896. Serial No. 605,448. (No model.) Patented in England December 12, 1894, No. 24,134.

To all whom it may concern:

Be it known that I, CHARLES BEAUMONT, a citizen of the United Kingdom of Great Britain and Ireland, residing at Roubaix, in the 5 Department du Nord, France, have invented certain new and useful Improvements in Hair-Pin-Making Machinery, (patented in Great Britain December 12, 1894, No. 24,134,) of which the following is a specification.

10 This invention relates to machinery employed in the production or manufacture of hair-pins and other similar articles having ball-points.

In the machine constructed for the purpose 15 of this invention the wire is fed in lengths each of which is equal to the total length of the blank required for the production of the finished article. The wire having been fed is then held and cut. The blank thus formed 20 is seized at the center and bent to the required form. The ends of the article are then seized and the ball or other similar points are formed by suitable punches. If the article is 25 to be "waved" or otherwise further bent or shaped, this is accomplished while the article is still held for the formation of the points. The blank having thus been transformed into the completed article is released and falls into a receptacle below.

30 The accompanying drawings illustrate the apparatus by means of which this invention may be carried into effect and are hereinafter referred to.

Figure 1 is a plan of the machine. Fig. 2 35 is a longitudinal section. Figs. 3, 4, and 5 represent details of the construction. Figs. 6 and 7 represent, respectively, an undulated and a plain hair-pin with ball-points such as may be produced by the machine.

40 A is the framing, and B the table, of the machine. The wire D is fed by the lever a, which by its oscillatory motion reciprocates the carrier a' in the guiding-channels a''. The carrier is adapted to seize and carry the wire 45 in its forward stroke and to release it when moving back, as in other machines of a like character. The lever a is actuated by the cam 1. When the required length of wire has been fed, the lever b descends and holds 50 the wire, this lever being actuated to operate at the proper time by the cam 2. Then the knife c', which slides in the vertical slides W,

descends and cuts off the length of wire. The knife is operated by the cam 3 through the lever c. At the same instant the wire blank 55 is seized at the middle of its length by the end of the piece f and the former g actuated through the slide d by the cam 4. Then the jaws h, actuated through the slide e and plate e' by the cam 5, move forward and bend the 60 blank to the form of a hair-pin, while the continued motion of the piece f finally presents the points of the pin to the matrices p p', through the perforations q q' of which they pass to such a distance that the points protrude on the opposite side. (See Figs. 1, 2, and 5.)

The perforations of the matrices may be widened at the entrance to facilitate the entrance of the pin-points. The lower part p' 70 of the matrix is carried upon the vertically-reciprocating plate m, which is operated through the lever u by the cam 6. The upper part p of the matrix is fixed. As soon as the points have been inserted in the matrices the 75 lower part p' moves upward and the ends of the pin are thus seized and held while the ball-points are formed by the punches l l', which are further illustrated in front elevation by Fig. 3. The punches are forced simultaneously against the ends of the blank to form the points by means of the lever j, the sliding rod i, and the cam 7. Motion is preferably communicated from the lever j to the punches l l' by means of the adjustable screws r r' in 80 the working direction. The punches, lever, and slide-rod are respectively returned by the springs y y'.

When it is desired to form an undulation in each limb of the pin, this is effected while 90 the pin is still held in the matrices by the pressers n n' and the stops t t', the two pressers simultaneously forcing the parts of the limbs between them between the stops, and thus producing the bend in each limb. The 95 pressers are actuated by the arms k k', on each of which there is an inclined part. The arm k is moved by the action of the rod i, on which there is fixed an inclined part k'', which comes into contact with the inclined 100 part of k, and thus moves it away from i. On the lever j there is an extension j', having a beveled end which operates in contact with the inclined part of the arm k', and thus

moves it simultaneously with the arm *k*. The arms *k k'* thus cause the simultaneous approach of the pressers, and the amount of their motion may be regulated by the adjusting-screws, the heads of which form contacts with the arms. The return of the pressers may be effected by means of the springs, as indicated by Fig. 1. The ball-points having thus been formed, the matrices open and the pin is withdrawn by the return motion of the former *g* and falls into a receiver placed below.

The described devices for producing the undulation in the limbs of the pin may be considerably modified, if used, according to results desired. As illustrated, the stops *t t'* are fixed upon a removable bracket *o*, Fig. 4, in the vertical member of which slots are formed for the passage of the fixing bolts or screws. More than two stops, with a corresponding increase in the number of presser-points, may be employed if it be desired to produce more than a single undulation.

Having now particularly described and ascertained the nature of my said invention and in what manner the same is to be performed, I declare that what I claim is—

1. In machines for making hair-pins the combination of a former, a seizing-piece for pressing the wire against the former, bending-jaws, a pair of matrices for holding the ends

of the pins and pressers and stops for undulating the pins.

2. In machines for making hair-pins the combination of a former, a seizing-piece, 35 bending-jaws, a pair of matrices for holding the ends of the pins and parallel punches for forming "ball-points."

3. In machines for making hair-pins, the combination and arrangement of the piece *f* 40 and former *g*, the jaws *h* actuated by a cam 5, the matrices *p p'*, and punches *l l'*, all co-operating to bend and point the pins, substantially as set forth with reference to the accompanying drawings.

4. In machines for making hair-pins, the combination and arrangement of the piece *f* and former *g*, the jaws *h* actuated by a cam 5, the matrices *p p'*, the punches *l l'*, and the pressers and stops *n n' t t'*, all co-operating to 50 bend, point and undulate the pins, substantially as set forth with reference to the accompanying drawings.

In testimony that I claim the foregoing as my invention I have signed my name, in presence of two witnesses, this 30th day of July, 1896.

CHARLES BEAUMONT.
